UNITED STATES PATENT OFFICE.

MORRIS F. STEIN, OF PHILADELPHIA, PENNSYLVANIA.

SWITCH.

Application filed January 9, 1922. Serial No. 527,853.

To all whom it may concern:

Be it known that I, MORRIS F. STEIN, a citizen of the United States, residing in the city and county of Philadelphia, State 5 of Pennsylvania, have invented new and useful Switches, of which the following is a specification.

The object of my invention is to provide a novel switch or detector for the purpose 10 of testing the ignition system in any cylinder of an internal combustion engine of conventional type, such as are commonly used in automobiles, trucks or other self-propelled vehicles.

Another object of this invention is to 15 provide novel means for testing the coils or spark plugs or grounded or disconnected wires on any ignition or wiring system.

It further consists of other novel features 20 of construction, all as will be hereinafter fully set forth.

For the purpose of illustrating my invention, I have shown in the accompanying drawings a form thereof which is at present 25 preferred by me, since it will give in practice satisfactory and reliable results, although it is to be understood that the various instrumentalities of which my invention consists can be variously arranged and organized 30 and that my invention is not limited to the precise arrangement and organization of these instrumentalities as herein shown and described.

Figure 1 represents a fragmentary perspective view of an instrument board of a motor vehicle, showing my invention attached to the dash thereof.

Figure 2 represents a section on line 2—2 Figure 1.

Figure 3 represents a section on line 3—3 Figure 2.

Figure 4 represents a section on line 4—4 Figure 3.

Figure 5 represents a side view of my invention.

Figure 6 represents a fragmentary view showing one of the knife blades in a neutral position.

Figure 7 represents a wiring diagram.

Similar numerals of reference indicate corresponding parts.

1 designates my novel switch or detector, which is applicable to the gas engine or ignition system of a motor vehicle, aeroplane 55 or the like.

In Figure 1 my invention is shown as

attached to the instrument board of a motor vehicle, the detector 1 comprising a casing or shell 2, having the lugs 3 thereon, through which suitable fastening devices pass. 60

4 designates an insulated disc which is fastened to the inner periphery of the casing 2 in any conventional manner, said disc being adapted to support the bolt 5 on which are rotatably mounted the knife blades 6, 65 7, 8 and 9, said blades being held in assembled position by a nut or the like.

10, 11, 12 and 13 designate the switch contacts, which receive said knife blades 6, 7, 8 and 9, said contacts being electrically connected to the lead wires of the 70 spark plug circuit.

14, 15, 16 and 17 are sockets or contacts of the same type, but are connected to the coil box, which may be seen more clearly 75 from Figures 1, 3 and 7.

Each knife blade has the oppositely located contact lugs 18 and 19, and projects through the slots 20 of the casing 2 and terminates in the insulated knobs or handles 80 21, whose lower portion 22 fits tightly against the both sides of the offset portions of the slots 20, thus frictionally maintaining the same in any position desired.

Both the spark plug and coil contacts 85 are fastened to the disc 4 by the binding posts composed of the screws or bolts 23 and nuts 24.

25 designates radially arranged insulated separators adapted to separate and insulate 90 the coil and spark plug sockets to prevent any possible short circuiting.

26 represents an inner cylindrical insulated lining, used to insulate the casing from the circuits. 95

The recess 27 in the insulation 4 is adapted to receive the member 28, the spring 29 and the plunger 30, said members comprising a ground circuit, grounded by way of the casing 2 and the screws 31 to the instrument board, as shown in Figure 2.

When the instrument board is of some insulating material, a wire 33 is used to ground to the cylinder.

34 designates a rear insulating disc used 105 to insulate all wires, from the instrument board.

The casing 1 is constructed in a novel manner, having a flanged annulus 35 in engagement with its front, said annulus holding the glass, mica or any other transparent material 36 therein. 110

The contacts or sockets 10, 11, 12, 13 are directly connected to the spark plug system, the socket 10 being connected to cylinder "A" by the wire 37, the socket 11 to the cylinder 5 "B" by the wire 38, the socket 12 to the cylinder "C" by the wire 39, the socket 13 to the cylinder "D" by the wire 40.

The sockets 14, 15, 16 and 17 are connected to the coil box 41 by the wires 42, 43, 44, 45 10 respectively.

The operation is as follows:—

When all the cylinders are firing properly, the knife blades are in a neutral position, as shown in Figure 6.

15 When, for example, the spark plug in cylinder "A" is to be tested, the knife blade 6 is positioned about one eighth of an inch ($\frac{1}{8}$ ") away from the contact 10, and if the spark plug in said cylinder is in good working order, a spark will be created at the 20 spark gap thus formed.

If the spark plug is grounded in any way, as by soot or carbon on the electrodes, or if 25 said electrodes are in contact with each other, no spark will be created, showing that the plug being tested is inoperative.

If the spark plug of cylinder "A" being tested is in good condition and said blade 6 contacts with the contact 10, no spark will 30 be created by the plug of said cylinder "A" and the motor will slightly slow down.

When the motor is used in a self-propelled vehicle and is under a heavy load or climbing a steep grade and one cylinder seems to 35 miss, and it is desired to ascertain which one is missing, the knife blades or switches are opened and closed, one after the other in sequence. This will cut off each cylinder separately and independently and cut down 40 the power in the cylinders which are not missing, but when the switch of the bad cylinder is closed, it will make no difference in the operation of the motor, thus indicating the cylinder which is missing.

45 When testing the coils of the coil box 41, the knife blades 6, 7, 8 and 9 are closed on the coil sockets 17, 16, 15, 14 respectively, as shown in dotted lines in Figure 3, whereupon if the coils are in proper condition 50 they will give a buzzing sound.

When the ignition system is to be tested, the knife blades or switches are in a neutral position as shown in Figure 6, or about one quarter of an inch ($\frac{1}{4}$ ") away from a spark 55 plug contact 10, the lead wires from the coil box to the spark plugs are disconnected and at this point, if the ignition system is in proper condition, there will be a jump spark between said blade and contact member.

60 It will be understood from the foregoing that all the knife blades 6, 7, 8 and 9 during the normal operation of the motor are normally positioned as seen in Figure 6, and that so long as all the spark plugs are functioning properly, nothing happens, but in 65

case one of the electrodes of the spark plugs is burned off, or damaged in any way so that it will interrupt the completion of the spark between the central electrode and the shell of said plug, it will create a longer and stronger spark between said knife blades and spark plug contacts, it being understood that there is no resistance in the spark plug, the spark between one knife blade and contact being intensified.

70 It will be apparent from the foregoing that my device can be very readily assembled and installed upon the instrument board or other support, and by making the contour of the casing preferably cylindrical and arranging the offset slots 20 so that the ends of the knife blades project therefrom diametrically or radially, a pleasing appearance is given to the device when it is installed in position.

75 The provision of the annulus 35 with its transparent cover 36 prevents the entrance of dirt or dust to the interior of the casing and the transversely located disk or insulation 4 serves as an effective support for the binding posts and their contacts, together with the switch elements and their adjuncts, all the parts being readily accessible for the 80 purposes of inspection, replacement or repair, as is evident.

85 It will be evident that suitable insulation is provided at all the points where insulation is required, as will be evident to those skilled in the art.

90 Having thus described my invention, what I claim as new and desire to secure by Letters Patent, is:—

1. In a device of the character stated, a 95 casing, an insulating member arranged transversely therein, a central support in the latter, knife blades having their inner ends rotatably mounted on said support and their outer ends projecting through slots in said casing, sets of radially arranged contacts arranged in pairs between said knife 100 blades located in said casing, and means for frictionally locking with the casing the outer ends of said blades in their extreme positions.

105 2. In a device of the character stated, a casing of annular contour, a disk shaped insulating member transversely supported in said casing intermediate of its front and rear, a central support in said insulating member, knife blades radially arranged and having their inner ends rotatably mounted on said support and their outer ends projecting through offset slots in said casing, a series of contacts for said knife blades located in said casing, a transparent cover for 110 said casing, and means for frictionally locking with the casing the outer end of a blade in its extreme position.

115 3. In a device of the character stated, an annular casing, an inner insulating lining 120

for the sides and rear of said casing, an insulating disk shaped member transversely located within said casing intermediate of the front and rear thereof, a central support in said insulating member, knife blades having their inner ends rotatably mounted on said support and their outer ends projecting through offset slots in said casing, a series of contacts for said knife blades located on said intermediate disk shaped insulating member within said casing, a transparent cover for said casing, and means for frictionally locking with the casing the outer ends of said blades in their extreme positions.

4. In a device of the character stated, a casing, insulation for the inner periphery and rear portion thereof, an insulating member extending transversely of said casing intermediate of its front and rear, a central support in said insulating member, knife blades having their inner ends rotatably mounted on said support and their outer ends projecting through offset slots in the walls of said casing, a series of contacts located on each side of said knife blades within said casing and means for frictionally locking with the casing the outer ends of said knife blades in their extreme positions.

5. In a device of the character stated, a casing having slots, an insulating member arranged transversely therein and interme-

diate of the front and rear thereof, a plurality of radially arranged knife blades rotatably carried by said insulated member, the outer terminals of said blades projecting through the slots in the walls of said casing, the rear of said insulating member being provided with binding posts for the conductors leading to the elements to be tested, an insulating lining for the inner periphery of said casing, and an insulating plate for the rear of said casing.

6. In a device of the character stated, a casing having offset slots, an insulating member arranged transversely therein and intermediate of the front and rear thereof, a plurality of radially arranged knife blades rotatably mounted on a support carried by said casing, the outer terminals of said blades projecting through the offset slots in the walls of said casing, the rear of said insulating member being provided with binding posts for the conductors leading to the elements to be tested, an insulating lining for the inner periphery of said casing, insulation for the rear of said casing, an annulus in engagement with the outer front of said casing and a cover of transparent material carried in said annulus.
